CLAIM

The ornamental design for a combined vest and harness, as shown and described.

DESCRIPTION

FIG. 1 is a front elevational view of a combined vest and harness showing our new design;

FIG. 2 is a rear view thereof;

FIG. 3 is a left side view thereof;

FIG. 4 is a right side view thereof;

FIG. 5 is a top plan view thereof; and,

FIG. 6 is a bottom view thereof.

The broken lines shown in FIGS. 1 and 2 are understood to represent conventional stitching.
